US0D1068413S

(12) **United States Design Patent** (10) **Patent No.:** **US D1,068,413 S**
(45) **Date of Patent:** **** Apr. 1, 2025**

(54) **MEAT SHREDDER**

(71) Applicant: **Zhencai Zheng**, Fujian (CN)
(72) Inventor: **Zhencai Zheng**, Fujian (CN)
(**) Term: **15 Years**
(21) Appl. No.: **29/894,675**
(22) Filed: **Jun. 13, 2023**
(51) LOC (15) Cl. **07-04**
(52) U.S. Cl.
USPC **D7/693; D7/372**

(57) **CLAIM**

The ornamental design for a meat shredder as shown and described.

DESCRIPTION

FIG. 1 is a top perspective view of a meat shredder, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top perspective view of the meat shredder in a detached state; and,

FIG. 10 is a bottom perspective view thereof.

The broken lines in the figures are for the purpose of illustrating portions of the meat shredder which form no part of the claimed design.

1 Claim, 8 Drawing Sheets
